UNITED STATES PATENT OFFICE.

ELMER E. SLOCOMB, DECEASED, LATE OF WINTHROP, MASSACHUSETTS, BY HAROLD C. SLOCOMB, ADMINISTRATOR, OF WINTHROP, MASSACHUSETTS, AND FRED W. MCARDLE, OF BOSTON, MASSACHUSETTS, ASSIGNEES, BY DIRECT AND MESNE ASSIGNMENTS, TO PNEUMATIC SCALE CORPORATION, LIMITED, OF NORFOLK DOWNS, MASSACHUSETTS, A CORPORATION OF MASSACHUSETTS.

PACKAGING MACHINE.

Application filed April 14, 1924. Serial No. 706,388.

Our invention relates to improvements in machines for packaging goods, more particularly to that class of machines in which the product to be packaged, is wrapped or enclosed by covering material, in distinction from that class in which the product is deposited in a container.

One object of our invention is to provide a machine which is adapted to wrap or enclose portions of a product within suitable wrapping material, such as paper or cloth.

Another object of our invention is to coordinate the several devices and parts of our invention, to the end that the several operations shall be performed successively and continuously for the purpose of providing a rapid, economical and efficient packaging machine of this class.

Our invention consists in novelties of construction and in the coordination of novel devices to accomplish the foregoing objects, all of which will be hereinafter described and illustrated in the following specifications and the drawings forming a part thereof.

A preferred form of our machine comprises a carrier, intermittently rotated, to which is fed, during the period of rest, a strip of wrapping material which is then cut to suitable length. The succeeding rotation of the carrier, transfers the portion of wrapping material to a position where the product to be packaged, may be deposited thereon during the succeeding period of rest, the portion of product deposited, and wrapping material fed to the carrier and cut to length for another package. Successive operations form the wrapping material about the product, secure by means of wire the opening of the package formed, trim projecting wrapping material and discharge the package from the machine. With the exception of the enclosing operation, the several operations are performed on successive packages during the rest period of the carrier, the forming of the package being done as the wrapping material together with the superimposed product, is transferred to the succeeding station by the carrier.

We do not confine our invention to the form shown, as variations in construction

and operation may be used without departing from the spirit and scope of this invention.

In the drawings:

- In the drawings, the bed 1, is mounted on posts, 2 and supports the operative parts necessary to accomplish the foregoing objects.
- 40 The posts, 2 are supported by a suitable bench 3, and secured to this bench are bearings 4, in which is journaled the main shaft 5, to which is secured the several cams and pulleys by means of which the several operations are controlled. Projecting upwardly from the bed 1, is the post 6, (Figures 4 and 5) which forms a journal for the spider 7, to the arms of which are secured the segment plates 8, forming a surface on which the packages are supported and transferred from station to station, as the spider is rotated step by step. The spider and plates will be hereinafter referred to as carrier A.
- 45 For rotating carrier A, any suitable mechanism may be used, but we prefer to employ the so called Geneva movement which comprises a slotted member 9, (Figure 5) secured to the hub of the spider 7. This slotted
- 50 member is engaged by the roll 10, journaled on the stud 11 which projects from the arm 12, secured to the shaft 13. The miter gear 14 also secured to this shaft meshes with the miter gear 15 secured to the main shaft 5.
- 55 and is driven thereby. As the arm 12 is rotated, the roll 10 engages one of the slots 16 in the member 9, and the carrier A is rotated through a predetermined arc which in this machine is assumed as 60 degrees. As the roll leaves the slot 16, an extension 17, 70 formed concentric with the hub of the arm 12, engages the socket 18, formed in the member 9, rotating therein and locking the member until the roll is about to engage the next slot, at which time the extension 17, permits 75 the rotative action due to the action of the roll in the succeeding slot.
- 80 Mounted on the segment plates 8 are the several forming units B which will be herein-after described, slots being provided in the plates to permit of the action of the fingers on the wrapping material to enclose the product deposited thereon.
- 85 The wrapping material is delivered to the unobstructed surface of the carrier plate at station C, and is there cut to suitable length. This combined operation is performed in the following manner:—Referring to Figures 2 to 9, a supporting frame 20 is secured to the extension 21, of the bed 1. In this frame are 90 journaled shafts to which are secured the feed rolls 22, 23, 24, (Figures 5 to 9).
- 95 The wrapping material *a* is of predetermined width and is drawn from a supply roll, not shown. To operate the feed rolls, 100 we provide the following mechanism. Secured to the shaft 25, on which is mounted the roll 22, is a ratchet 26. Engaging the ratchet is a pawl 27, swiveled on a stud 28, projecting from an arm 29, a spring 30 serving to exert a yielding pressure on the pawl to insure engagement with the ratchet 26. The arm 29 is rotatable on the shaft 25, and is provided with a hub 31, to which is secured a pinion 32, meshing with a segment 105 33. This segment is swivelled on a stud 34 projecting from an extension 35, formed on the supporting frame 20.
- 110 The segment 33 is extended at 36, and the slot 37 therein is adapted to receive a stud 38, which serves as a journal for one end of the pitman 39, the other end of which is secured to the yoke 40, which is adapted to slidably engage the main shaft 5, on which is rigidly mounted the cam 41. A roll 42, journaled on the stud 43 projecting from an extension of the yoke 40, bears against the cam, which thus controls, through the mechanism described, the oscillation of the pawl arm 29, to produce a step movement of the roll 22.
- 115 The spring 44 attached to the yoke 40, exerts a yielding pressure to preserve the contact between the roll and the cam. Secured to the roll shafts, are intermeshing gears 45—46 which insure the same peripheral speed of the rolls. By adjustment of the position of the stud 38 in the slot 37, the rolls are rotated through arcs corresponding in length to that of the wrapping material required, the rolls 23—24 being journaled in 120 125 130

bearings 47-48 which slidably engage the supporting frame, springs 49 exerting a pressure to insure a yielding contact of the rolls. The action of the feed rolls is such as to draw the wrapping material from the source of supply and to push the free end forward to its position on the carrier A, symmetrically over one of the forming units B, which is secured thereto. The character of the wrapping material may be such that waves will form as the feed rolls push it forward to position, and we provide a supplementary feeding device adapted to cooperate with the main feeding rolls. The construction and operation of this device is as follows:—Swivelled on the shaft 50 are the arms 51, cross braced at 52 thus forming a forked member, in the outer end of which is journaled the shaft 53, to which is secured the roll 54, which is preferably covered with a yielding material as at 55. Secured to the shafts 50 and 53 are sprockets 56-57 connected by the chain 58. It is essential that the peripheral speed of the roll 54 shall exceed that of the rolls 22-23, in order that it may exert a pulling action on the wrapping material, and this may be accomplished by means of different sized sprockets as shown, or by increasing the size of the roll 54. Springs 59 may be used to exert a yielding pressure on the roll through extensions 60 formed on the arms 51.

A bridge piece 61, secured to the supporting frame 20, is provided, which overlaps the carrier A, and over this the wrapping material slides and is engaged by the roll 54.

It will be evident that the roll 54 would interfere with the transfer of the severed wrapping material by the carrier A, unless released from contact after the feeding was completed, and the following means are provided to accomplish this:—The rods 62, having bearings in the supporting frame 20, engage the lugs 63 on the cross brace 52. The lower ends of these rods are supported at 64 on the levers 65, which are secured to the shaft 66 which is journaled in the bed 1. A lever 67, also secured to the shaft 66 is provided at its outer end with a stud 68 on which is journaled the roll 69 which bears on the cam 70, secured to the main shaft 5. This cam is so formed that, as it rotates, the roll 54 is raised from contact with the wrapping material a when the feeding action is completed, and when the feeding operation is under way, the roll is lowered to contact with the wrapping material a when the advancing edge thereof is substantially under the axis of the roll 54. When the wrapping material has been fed to position on the carrier A, the feeding action ceases, and the projecting portion is severed from the web in the following manner:—The shear blade 75 is swivelled to the supporting frame 20 at 76, and is adapted to slidably engage a fixed blade 77, rigid with the supporting frame, and over which the wrapping ma-

terial passes as it is fed to position. The shear blade 75 is connected near its outer end by means of the pitman 78, with one end of a lever 79, journaled at 80 on a stud projecting from the bed 1. This lever is operated in a manner similar to that of the lever 67 by the cam 81, secured to the main shaft 5. To insure a shearing action between the blades of the shears, we have provided a guide plate 82, which exerts a yielding pressure on the outer side of the shear blade 75 as it is operated.

This blade is supported on the stud 83 projecting from supporting frame 20, the nut 84 and spring 85 providing an adjustable yielding pressure required.

The wrapping material, as stated rests on the carrier A, symmetrically disposed relative to the unit B, and it is essential that it be retained in this relation as the carrier is rotated.

A preferred mechanism for insuring this condition is shown in Figure 19-20 in which 90 is a bracket secured to the fixed hub 91 which is integral with the segment 92 (Figures 4 and 26) which also furnishes a support for other elements hereinafter described. The hub 91 is rigidly secured to the post 6; a bell crank 93 is journaled on the pin 94 in ears of the bracket 90, and is adapted to oscillate about this pin. The ends of the bell crank arms are forked and at 95 is pivoted the holder 96. This holder is chambered at 97 to receive the plunger 98 rigidly secured at 99. The stripping bushing 100 is slidable within this chamber and on the plunger 98, and yieldingly pressed downward by the spring 101. A pin 102 projecting from the plunger 98 engages the slot 103 in the bushing 100, permitting a sliding movement thereof relative to plunger 98 and chamber 97. The link 104 is swiveled to the holder 96 and the bracket 90 to insure a vertical movement of the holder relative to the carrier A.

The other forked end of the bell crank is adapted to engage a holder 105 pivoted at 106; this holder is chambered to receive the spring 108 which is adapted to exert a yielding pressure on the collar 109 secured to the rod 110, a similar collar being secured to the rod at 111. This rod has a sliding bearing at 112 in the holder 105, and in the bracket 90 at 113, a spring 114 acting between the projection 113 and a collar 115 secured to the rod (Figure 4) to exert a yielding pressure to keep the bell crank normally in a position in which the holder 96 will be raised from the carrier A.

The rod 110 is extended at 116 to abut and act in unison with the package trimming unit F, as will hereinafter be more clearly explained. The bearing 117 projecting from the segment 92 provides a support for the rod 110 near the cutting unit F.

The plunger 98 is formed at its lower end with a blade 118 adapted to engage the wrapping material *a* and force it downwardly to engage clamping members 119 which have a 5 sliding bearing in the forked element 120, which is rigidly secured to the plate 8 of the carrier *A* the plate being provided with openings 121 through which the plunger acts.

The clamping members 119 are yieldingly held in contact with each other by means of the springs 122, abutting against the pins 123 projecting from the forked element 120. Pins 124, limit the movement of the clamping members, to insure an approximate central position of the clamping faces relative to the axis of the plunger 118.

The action of this device is as follows:—
When the section of wrapping material is fed to the carrier A and severed, the end 125
20 of the rod 110 is operated by the trimming unit F and the bell crank 93 is rocked. The blade 118 engages the wrapping material *a* pressing it downward and between the clamping members 119, which have wedge
25 shaped faces which enable the blade 118 to separate them and force a fold of the wrapping material between the ends as in Figure 21.

The slotted bushing 100 rests on the plate segment 8 and when the blade is withdrawn, acts as a stripper to prevent the withdrawal of the wrapping material which is thus clamped at or near the center of the section, by the members 119 (Figure 22).

35 The yielding pressure exerted by the springs 122 is slight, but sufficient to clamp the wrapping material during succeeding operations, yet to allow a release of the finished package with slight resistance. In the succeeding cycle the carrier A is rotated to bring the section of wrapping material to station D where portion of the product to be packaged, is deposited at or near the center of the section.

45 In the particular machine illustrated we have shown a device for delivering a predetermined portion of tea to each section of wrapping material, when it arrives at station D. It is evident however that other products 50 may be deposited by suitable devices. The device for depositing tea and the like is constructed as follows:—

55 A hopper 130 is rigidly supported above the carrier A, its axis being substantially central with the section of wrapping material when it is at station D. This hopper is supplied in any suitable manner with the product to be packaged, and may have within, a breaker of suitable design to prepare the
60 product for delivery.

As herein shown this breaker consists of a series of mutilated discs 131 secured to a rotating shaft 132 and spaced to alternate with fixed projections 133 which form a comb like member secured to the hopper. As the shaft

132 is rotated by means of the belt 134 (Figure 3) and pulleys 135—136 from the main shaft 5, the product is comminuted and falls through the nozzle into a measuring device. This may be of any suitable construction but we prefer to use the following:

Secured to the lower end 137 of the hopper 130 is a casing 138, with a passage therethrough in substantial alignment with the lower opening of the hopper. Transverse openings are adapted to receive the headers 139—140 which are mounted on the shaft 141. 75

The header 139 is provided with an extension hub 142 journaled in the cap 143 which is secured to the casing 138. The header 139 is rigid with the shaft 141 but the header 140 is slideable thereon and is provided with an extension hub 144 slotted to permit of a clamping action on the shaft through the medium of a clamping nut 145. 80 85

The headers are slotted to receive blades 146 which are secured to the header 139 but are slideable in the header 140. These blades are adapted to form compartments 147 into which the contents of the hopper fall, as the shaft 141 is rotated. The slideable header 140 provides a means for changing the amount which is contained in the compartments as shown in Figures 10-12.

The transverse openings thus form bearings for the headers 139 and 140 as the shaft 141 is rotated. 95

The shaft 141 together with the compartments formed as above, is intermittently rotated through the medium of the ratchet 150 100 secured to the shaft 141. A pawl 151 is swiveled at 152 on the pawl arm 153, a spring 154 insuring a constant bearing on the ratchet face. This pawl arm is rigid with the pinion 155 which is loosely mounted on the shaft 105 141, endwise movement being limited by the collar 156, rigid with the shaft 141.

Meshing with the pinion 155 is the segment 157 (Figure 3) swiveled at 158 on a stud projecting from the casing 138. This segment is provided with a slotted arm 159, and a pitman 160 is swiveled to the stud 161 which may be adjusted in the slot. The object of this adjustment is to provide a means to regulate the angular oscillation of the pawl arm to insure that the compartments shall register with the opening in the hopper. The lower end of the pitman 160 is swiveled to the lever 162 and the lever is rigid with shaft 163 journaled at 164-165 in the bed 1 (Figure 6). 110 115 120

Rigid with the shaft 163 is the cam lever 166 to which is swivelled the roll 167, adapted to engage the periphery of the cam 168 secured to the shaft 5. 125

As this shaft rotates an intermittent oscillation is imparted to the pawl arm 153, by means of which the compartments 147 are rotated (Figure 11). When the compartment 147 is aligned relative to the opening 130

169 in the casing 138 as at *b*, the portion to be deposited fills the compartment, which is rotated to position *c* in the next cycle of the machine and to *d* in the succeeding cycle, 5 at which time the contents are dumped upon the section of wrapping material *a*, through the opening 170 in the casing. To prevent the functioning of this device at times when the machine is being adjusted for a run, we 10 have provided a finger lever 171 which is swivelled on the stud 172 projecting from the casing 138. In normal position this lever is in the position shown in full (Figure 13) an extension 173 engaging the hub 174 of the 15 cap 143 to limit rotation. When it is required that this device should cease to function, the finger lever 171 is rocked to engage the under side of the pawl arm 153 as shown in broken lines (Figure 13). The effect is 20 to interrupt the operation of the cam lever 166 as the device is locked in such position that the periphery of the cam 168 engages the roll 167 only at its greatest radius. A spring 275 abutting the head of the stud 172 25 and the side of the lever 171 furnishes sufficient frictional resistance to retain the lever 171 in either operating or nonoperating position.

As the shaft 5 rotates, the carrier A transfers the section of wrapping material together with the superimposed portion of product, from station D to station E and it is during this movement of the carrier that the material *a* is wrapped about the portion 30 to form a sack shaped package. As heretofore stated the package forming units B are secured to the under sides of the segment plates 8 of the carrier A. Each unit consists of three sets of fingers 175, 177, 179 35 (Figures 15 to 18) hinged respectively in forked members 176, 178, 120.

The forked members 176, 178 are mounted on the stud 180 which is shouldered at 181 and threaded at 182 to screw into member 40 120 which is secured to one of the segment plates 8. When the stud is tightened, the shoulder 181 engages the forked member 176 and clamps it and member 178 against member 120. Preferably all the fingers are provided near their extremities with projections 45 which insure a broader surface to engage the wrapping material *a*. Slidably mounted on the stud 180 is a cup 183 adapted to engage at 184 with a cam track 1860 suitably and rigidly mounted, on the bed 1. The rim of the cup 50 is adapted to engage the fingers 175, 177 and the cam track is so formed that as the cup rides thereon, it is moved upward on the stud 180 transmitting a movement to the fingers, which swing on their respective hinges.

These two sets of fingers swing substantially in unison, and operate through slots 55 1850 formed in the segment plates 8. Normally the extremities of all the fingers are 60 below the surface of the plate on which rests

the section of wrapping material *a*, symmetrically disposed relative to the finger groups beneath.

As the cup rises the extremities of the fingers 175 and 177 engage the wrapping material near the edges, forming it into an approximate saucer shape in the middle of which reposes the portion of product to be packaged.

The normal position of the fingers is shown 75 at G Figure 17. It will be noted that fingers 179 are not engaged by the cup 183, which may be explained as follows:—As the saucer shape of the wrapping material becomes more pronounced waves are formed between contiguous fingers as shown diagrammatically in Figure 14^a. The wave formation increases as the fingers continue their upward swing and the waves become folds unless the tendency is corrected, which is the office of the 80 fingers 179. It is essential that the extremities of these fingers engage the waves thus formed and push them within the finger ends 85 185, 186. To accomplish this we have provided means for swinging these fingers 90 through a larger arc and in a shorter period than that of the fingers 175, 177.

Projecting on both sides from one set of fingers which we have assumed as 177, are the 95 extensions 187. These extensions are adapted to engage the outer edges of the fingers 179 after the other fingers have formed the wrapping material into a saucer shape. When the wrapping material has assumed substantially the shape shown at H, Figure 100 17, the wave formation is marked and the crests are engaged by the extremities 188 of the fingers 179. At about this point it is essential that the material be pushed within the grouping extremities 185, 186 of the fingers 105 175—177 and the further action of the projections 187 on the fingers 179 cause them to 110 function as shown at J Figure 18 and the edges of the wrapping material are crimped within the extremities of the three sets of 115 fingers. The continued action swings the fingers 179 ahead of the other sets which have by this time accomplished their particular function, and at the extreme travel of the fingers as shown in Figures 14, 15 and at K Figure 18, the open folds of the formed package have been compressed within the extremities 188 and are held in position until the superfluous wrapping material is severed 120 from the completed package at station F.

With thin and flimsy wrapping material it is advisable to provide guides 190—191 Figure 4, 30, 31 to assist the fingers in forming the package. For clearness these guides are omitted in other figures. Their action is to 125 raise the outer and inner edges of the section of wrapping material, being formed to cooperate with the units B.

The guide 190 is secured to the arc 92 and 130 191 to one of the fixed elements 216 positioned

at station E, at which station a metal wire is secured about the crimped neck of the package to form a closure thereto.

It is essential that the neck of the package immediately above the finger ends, be free from all overhanging ends of wrapping material in order that the wire closure may be properly applied by the mechanism presently to be described.

10 To insure this condition we employ a device for brushing up the overhanging ends, constructed as follows:—Referring to Figures 24, 25, 26 the shaft 195 is mounted in bearings 196 and 197 and is adapted to rotate therein.

15 Secured to this shaft is the arm 198 to which is fastened the blade 199 of sole leather or other similarly flexible material. The shaft is oscillated by means of a pinion 200 secured thereto and meshing with the rack 201, an extension of the rack which operates the wire feeding mechanism which will be presently described.

20 The position of this device is such that, the plane of oscillation of the center line of the blade 199 is substantially tangential to the path of travel of the axes of the packaging units B. Relative to the station E, the position of this device is such, that when one of the units B approaches this station, the blade 199 may be oscillated to follow and brush upwardly the overhanging ends of the wrapping material, and to retain them after the unit B has come to rest at station E. An auxiliary lever 202 swivelled at 203 on the segment 92 coacts with the brushing blade 199 to firmly hold the neck of the package while the wire closure is applied thereto, and is constructed as follows:—The pinion 204 is rigidly secured to the shaft 195 and is adapted to mesh with the segment 205 which is rigid with the stud 206 journalled at 207 on the segment 92.

25 To this shaft is rigidly secured the segment 208 meshing with idler pinion 209 swivelled on the stud 210 projecting from the segment 92. Integral with the hub of the arm 202 is the segment 211 adapted to engage the idler pinion 209. As the carrier A is rotated from station D to station E the package is formed as above explained. Surplus wrapping material projecting beyond the finger extremities of a unit B has a tendency to lag, due to the frictional resistance of the guides 190, 191.

30 This is especially the case as the neck of the package approaches the contracted area 212 formed by the guides. Figures 30, 31, 24.

35 The brushing device described is adapted to operate to follow the unit B and brush upwardly the dependent surplus wrapping material, completing its action substantially at the moment the unit B comes to rest at station E, at which station the neck of the package engages the socket 2120 formed in the lever 213. The arm 202 in turn follows closely

after the brushing blade but in a horizontal plane, the end of the arm being bifurcated at 2130 (Figures 24, 26, 30, 31) to clamp the neck of the package into the socket, above and below the wire closure to be subsequently applied. Figure 26^a is a diagrammatic view of the action of this device showing in full lines the positions of parts at the beginning of the action and in broken lines the conditions at the time the closure is about to be applied. The device for forming a closure about the neck of the package may for descriptive purposes be divided into two parts, the wire feeding and forming mechanism and the clinching mechanism. These are correlated and function as a complete device to feed and cut the wire used; to form a staple about the neck of the package; and to clinch the ends of the staple about the neck.

40 The wire is fed from a source of supply and cut to suitable length by any suitable method but in this particular case we prefer to employ the following construction:—Referring to Figures 3, 25, 26.

45 The stand 215 is rigidly mounted on the bed 1, at station E and serves as a support for the several elements required in the formation of the staple above noted. Secured to the top of the stand 215 is the holder 216 in which is journaled the shaft 217. Integral with this shaft is the grooved disc 218 (Figure 24). Secured to the other end of this shaft is the pinion 219 adapted to mesh with the gear 220. This gear is rigidly secured to the shaft 221, journaled in the arm 222 which is hinged at 223 to projecting ears 224 formed on the holder 216 (Figures 25, 31).

50 Secured to the other end of the shaft 221 and adapted to co-act with the disc 218 is the disc 225 milled on its periphery.

55 As these discs are rotated by means to be described the wire 226 is fed forward.

60 It is essential that there shall be sufficient pressure of the discs on the wire to insure that there be no slippage, and it is for this reason that the hinged arm is used for supporting the shaft 221. An extension 227 of this arm is yieldingly pressed from beneath by the spring (Figure 3) the stud 228 rigid relative to the holder serving as an arbor for the spring. This arbor is threaded and a nut 229 provides a means for adjusting the tension of the spring, and the pressure through the arm 222 and the disc 225 on the wire 226.

65 At times when adjusting the machine as a whole, it is advisable that the feeding of the wire be temporarily interrupted, and to secure this result without disconnection of parts, we have slotted the upper end of the stud 228 and have swiveled therein the cam lever 2280 which is adapted to depress the extension 227 and raise the milled disc from contact with the wire. This is particularly shown in Figure 25^a.

70 Mounted on the shaft 221 and adapted to

rotate thereon is the pawl arm 1227, projecting from which is the stud 1228 on which is swiveled the pawl 1229 adapted to engage the ratchet 230 which is rigidly secured to the 5 shaft 221. The spring 231 serves to exert a yielding pressure to maintain engagement of the pawl 1229 with the periphery of the ratchet 230. The pawl arm 1227 is provided with an extension hub to which is secured the 10 gear 232 which is adapted to engage the rack 201. It will be noted that this rack simultaneously operates the brushing device already described, and when these movements are completed the wire is fed ready to be 15 cut, and the neck of the package is clamped in position to have the staple formed about it.

To the lower end of the rack is swiveled at 233 one end of the pitman 234 (Figures 1, 3) the lower end of which is swiveled to 20 the bell crank 235, journaled on the stud 236, projecting from the bed 1. From the other arm of the bell crank projects the stud 237, on which is journalled the roll 238, adapted to engage the periphery of the cam 239 rigid 25 with the main shaft 5.

The spring 240 is secured to the bell crank and exerts a tension thereon to retain the roll 238 in contact with the cam 239. Swivelled on the stud 236 and similarly operated from 30 the cam 241 rigid with shaft 5, is the lever 242 connected by a pitman 243 with one end of the bell crank 244, journaled at 245 between the ears 246, integral with the stand 215. To the 35 other arm of the bell crank is swiveled the carrier 247 adapted to slide in the holder 216. Caps 248 and 249 secured to this holder complete a slide bearing for the carrier. It has been found convenient to make the bearing 196 for the shaft 195 integral with the cap 40 248 and to provide at 250 a retaining bearing for the rack 201. Secured to the carrier 247 is the plate 251 (Figures 30 to 42).

This plate is of hardened steel and is adapted to slide against the hardened liner 45 2510 which is pierced at 252 to permit the passage of the wire 226. The countersink 254 and the bushing 225 serve as guides to assist in threading the wire and in aligning it with the feed discs 218 and 225. The wire, 50 fed forward as already described, projects across the path of the plate 251, and as the carrier 247 is operated as above described, the advancing edge 256 of the plate 251 shears the wire.

55 As the wire is sheared there is a tendency for it to spring outwardly at its end, and as the shearing is completed to similarly react at the line of shearing, and we have provided yielding blades 257 and 258 secured 60 respectively by the caps 248, 249, to control this tendency and retain the severed wire in place.

Integral with the plate 251 is the shoulder 259 adapted to support the wire near its 65 severed end and secure to the under side of

the plate is a plate 260 which serves as a support for the other end of the wire and is bifurcated at 261 to engage and further compress and hold the neck of the package as the staple is formed. As thus described, the 70 wire rests in an inclined position in front of and advancing with the plate 251, and the staple is formed in an inclined position about the neck of the package in order that the ends may be clinched without interfering. 75

The plate 251 is slotted at 262 the slot being central with a line passing through the axis of the package to be closed. Slidably in this slot is an element 263 which is normally withdrawn as shown in Figure 36. 80

A plate 264 is hinged at 265 to the caps 248, 249 (Figures 24, 26) the spring 266 exerting a yielding pressure on the plate to retain it in a normally low position. The socket 2120 is formed near the free end of this plate, and 85 projecting downwardly from the plate and beyond the socket 2120 is the stud 267, Figures 30, 32, to 36.

This stud is so disposed that the inner side 90 of the neck of the bag engages the stud when held in the socket 2120 as described. The purpose of this stud is to form an abutment for the neck of the package as the staple is formed. As the plate 251 is advanced, the 95 wire engages midway of its length, with the neck of the package, and the continued advance of the plate forms the staple about the bag, (Figure 36), the edges of the slot 268 serving as a die, and the neck of the package supported by the stud 267 serving as an arbor, 100 the loop of the staple being pressed into the slot.

When the staple has been thus formed, 105 plate 264 is swung upwardly by means presently to be described and the continued advance of the plate forces the staple into a position in which the ends may be clinched as will be presently described. This final movement of the plate is utilized to advance the element 263, the forward end of which 269 is formed 110 to approximate the arc of the staple.

Swiveled at 270 on the carrier 247 is a lever, one end of which, 271, engages a slot 272 in the element 263. The other end of the lever 273 projects beyond the side of the carrier 247, 115 the guide way being relieved at 274 to permit free sliding movement of the carrier.

As the carrier approaches its extreme inward travel, the staple being formed, and the 120 abutment stud raised, the end of the lever 273 engages the abutment 2750, formed on the guide way and the lever is swiveled on its stud 270, acting to slide the element 263 forward, to engage the staple and press it forward, at the same time acting in conjunction 125 with elements already described to further compress the neck of the package, to the end that when the clinching operation is completed, the wire shall be tightly wound about the neck and form a positive closure. 130

The clinching operation which immediately succeeds the formation of the staple, is performed by the device which will now be described.

- 5 Journalled in the segment 92 is the quill 275 to the lower end of which is secured a hub 276, and to the upper end of which is secured the pinion 277 (Figure 27). To the under surface of the hub 276 is rigidly fastened the 10 segment plate 278 (Figures 27, 36 to 41). Journalled in the quill 275 is the shaft 279 to the lower end of which is secured a plate 280 similar to the plate 278, a pinion 281 like pinion 277 being secured to its upper end.
- 15 The edges of plates 278, 280 are concentric with the axis of the shaft and quill, and of like radius.

These plates are beveled from their contiguous faces, abutments being formed at 282 20 in plate 278 and at 283 in plate 280.

- When the staple is forced forward formed in an inclined position, the ends engage respectively the beveled edges of the plates one end being guided upward, and the other 25 downward, and the neck of the package is pressed and held against the feather edges of the segment plates 278, 280. The segment plates are oscillated in opposite directions and the abutments 282, 283 bend the ends of 30 the staple about the neck of the package, forming a complete closure. The progressive action of the staple is shown in Figures 36 to 41. In Figures 36, 37 the staple being formed, and about to be pressed forward, a 35 partial oscillation of the plates 278 and 280 causes the wedge 285, rigid with the upper face of the plate 278, to engage the outer end of the hinged plate 215 and to raise it, thus withdrawing the stud 267 and permitting 40 the advance of the staple as shown in Figures 38, 39 the completed closure being shown in Figures 40, 41.

The oscillation of the clinching plates is accomplished as follows:—The yoke 286 is 45 provided with rack sides 287, 288 adapted to mesh respectively with the pinions 277 and 281. These racks are slidable in a bearing formed on the segment 92, the yoke members being rigidly secured to form a single element. An extension 290 of the yoke, is swiveled to the upper end of the lever 291 (Figures 1, 3, 6,) which has a bearing in the bracket 292 rigidly secured to the bed 1. The lower end of the lever is swiveled at 293 to 50 the yoke connection 294, constructed and operating in a manner similar to the description of the yoke 40, the roll 295 on the projecting stud 296 engaging the cam 297 which operates through the mechanism described, to 55 clinch the ends of the wire to form the closure of the package.

When this operation is completed the clinching mechanism dwells until the staple forming and brushing devices have returned 60 to their initial positions, and the carrier A

has moved the package beyond the stud 267, at which time the clinching device returns to normal position while the closed package is transferred to the station F where the surplus wrapping material is sheared from 70 the package.

On account of the original shape of the section of wrapping material *a*, there will be a more or less uneven projection of material above the closure wire and at station F this 75 is sheared by a rotating cutter 300 secured to the rotatable shaft 301 journalled on the end of an arm 302 which is secured to one end of a shaft 303 (Figures 1, 2, 6). This shaft is journalled in the bracket 304, secured to the bed plate 1. To the lower end of this shaft 303 is secured the lever 305 which is oscillated by means of the yoke connection 306 and roll 307 from the cam 308 secured to the shaft 5, all in manner similar to that already described. The rotating cutter is driven by means of the pulley 310, secured to the upper end of the shaft 303, the belt 311 running over the idlers 312, 313 (Figures 1, 2, 4, 6) to the pulley 314 journalled on the 90 stud 315 projecting from the bracket 304. The pulley 314 is integral with a second pulley 3150 which is driven by the belt 317 from a pulley 3170 secured to the main shaft 5.

A tightener pulley 318 is journalled on a 95 stud projecting from the arm 319, which is journalled on the stud 320 projecting from bracket 304. Tension on the belt 311 is provided by means of a spring 321 which exerts a yielding pressure to swing the roll 100 against the belt, thus insuring traction.

It has been found advisable to employ means for brushing trailing wrapping material from the path of the rotary cutter as the package approaches station F and this 105 is done in like manner to that above described, the flexible blade 325 Figures 24, 26 being oscillated through the medium of the shaft 326 journalled at 327, 328 on the segment 92, the pinion 329 being secured to the inner 110 end of the shaft and adapted to mesh with the segment gear 205. As the formed package comes to rest at station F the arm 302 carrying the rotating cutter is oscillated to cause the axis of the cutter to swing toward the 115 axis of the formed package. As this movement starts, the rotating cutter engages the blade 330 yieldingly supported in a recess formed in the under side of segment 92. This blade acts as a shear blade to insure a clean 120 cut of the surplus wrapping material projecting above the closure.

As the rotating shear operates in conjunction with the blade 330, the cutter guard 331 presses closure *h* against the abutment 332 125 which is rigidly secured to the segment 92. This segment is positioned so that it is engaged by the free ends of the closure which is more firmly clinched and the ends embedded in the neck of the package.

While this is not an essential requirement, it insures against projecting ends of the wire. As the rotating cutter swings back to normal position, the carrier A transfers the finished package to station I, during which movement the fingers of the forming unit B are released, the cup 183 dropping from the cam track 180 at 333, to the position shown in broken lines Figure 14, the sleeve end 334 of the cup 183 engaging the abutment 335 formed on the stud 180 which thus limits the downward movement. The package thus resting at station I on the plate 8 and unsupported by the unit B, is brushed from the supporting surface by means of the flexible blade 336 secured to the arm 337, which is rigid with the shaft 338, journaled in the overhanging bracket 339. This flexible blade is oscillated in unison with, but in the opposite direction to the blade 325 depending from the shaft 326, the lever 340 rigid therewith, being connected by the pitman 341 to a similar lever 342 secured to the shaft 338.

As the blade oscillates, it engages the finished package and releases it from the clamping members 119, also releasing any of the fingers of the unit B which have perchance failed to drop to normal position. On the return oscillation, the package is brushed from the carrier A, and the segment together with the preceding one is clear, which permits the removal of any fragments which may remain, before the particular segment rotates to station C in readiness to receive another section of wrapping material.

From the foregoing it will be evident when the machine is in operation, every revolution of the shaft 5 rotates the carrier through one space from station to station.

The operations above described are performed simultaneously on the packages at the several stations, acting successively and progressively on each package, each operation being governed by the respective cams and pulleys secured to and rotating with the main shaft 5, the cams being correlated and coordinated with the mechanism employed for rotating the carrier A. We do not confine ourselves to the exact form of machine hereinbefore illustrated and described, as the details of construction and the operative mechanism may be varied without departing from the essential features of our invention.

Having described our invention, we claim:

1. A packaging machine, comprising a movable carrier; means for supplying a section of wrapping material to the carrier; means for depositing the product to be wrapped on the wrapping material; means for forming the wrapping material about the product, to form a sack like package; means for securing a wire or band about the free ends of the package, to serve as a closure thereto; and means for coordinating the ac-

tion of the several devices with the carrier for the purpose of performing the several operations on each package.

2. A packaging machine, comprising a movable carrier; means for supplying a section of wrapping material to the carrier; means for depositing the product to be wrapped on the wrapping material; means for varying the size of the portion; means for forming the wrapping material about the product to form a sack like package; means for securing a wire or band about the free ends of the package, to serve as a closure thereto; and means for coordinating the action of the several devices with the carrier for the purpose of performing the several operations on each package.

3. In a packaging machine, a carrier table; means for supplying wrapping material thereto; an element movably supported and adapted to depress a portion of the wrapping material within an opening in the carrier plate; yielding members adapted to engage the depressed portion and to retain the wrapping material in position relative to the carrier plate; and means for operating the depressing element.

4. In a packaging machine, a wrapping device comprising a plurality of finger elements adapted to engage a section of wrapping material, and to form a sack like package about a portion of a comminuted product deposited thereon; means for operating the fingers; means for securing the neck of the package by means of a wire or metal clip to form a sole closure.

5. In a packaging machine a wrapping device comprising a plurality of fingers hinged about a common axis, and adapted to swing in radially fixed relation thereto, for the purpose of engaging wrapping material, forming a sack like package about a product deposited thereon; means for swinging the fingers on their hinges; and means for retaining the package in form to enclose the product, and means for applying a wire or clip to the free edges of the wrapping material to serve as a closure.

6. In a packaging machine a wrapping device comprising a plurality of fingers hinged about a relatively fixed axis, and adapted to engage wrapping material, and to form a sack like package about a product deposited thereon; a plurality of secondary fingers similarly hinged, and adapted to swing for the purpose of cooperating with the primary fingers by pressing inwardly the folds that may form between the primary fingers; means for swinging the secondary fingers; and means for retaining the package in form to enclose the product.

7. In a packaging machine a wrapping device comprising a plurality of fingers hinged about a relatively fixed axis, and adapted to engage wrapping material, and to form a

- sack like package about a product deposited thereon; a plurality of secondary fingers similarly hinged, and adapted to swing for the purpose of cooperating with the primary fingers by pressing inwardly the folds that may form between the primary fingers; means for swinging the secondary fingers; means for retaining the package in form to enclose the product.
10. 8. In a packaging machine a wrapping device comprising a plurality of fingers hinged about a relatively fixed axis, and adapted to engage wrapping material, and to form a sack like package about a product deposited thereon; a plurality of secondary fingers similarly hinged, and adapted to swing for the purpose of cooperating with the primary fingers by pressing inwardly the folds that may form between the primary fingers; independent means for swinging the secondary fingers; and means for retaining the package in form to enclose the product.
9. In a packaging machine a wrapping device comprising a plurality of fingers hinged about a relatively fixed axis, and adapted to engage wrapping material, and to form a sack like package about a product deposited thereon; a plurality of secondary fingers similarly hinged, and adapted to swing for the purpose of cooperating with the primary fingers by pressing inwardly the folds that may form between the primary fingers; means whereby the secondary fingers may be swung by the action thereon of the primary fingers; means for retaining the package in form to enclose the product.
10. In a packaging machine a wrapping device comprising a plurality of fingers hinged about a relatively fixed axis, and adapted to engage wrapping material; and to form a sack like package about a product deposited thereon; a plurality of secondary fingers similarly hinged, and adapted to swing for the purpose of cooperating with the primary fingers by pressing inwardly the folds that may form between the primary fingers; means for swinging the secondary fingers through an
- arc greater than that of the primary fingers, for the purpose of engaging and pressing inward the folds formed between the primary fingers; means for swinging the primary fingers; and means for retaining the package in form to enclose the product.
11. In a packaging machine, a wrapping device comprising a plurality of fingers hinged about a relatively fixed axis, and adapted to engage wrapping material for the purpose of forming a sack like package; projections near the free ends of the fingers adapted to provide a broader area of contact with the wrapping material; means for swinging the fingers on their hinges for the purpose set forth; and means for retaining the package in form to enclose the product.
12. In a packaging machine a movable table adapted to support a section of wrapping material, means for moving the table step by step to coordinate with other means for depositing a portion of product upon the section of wrapping material; with independent means for enclosing the product within the wrapping material; and with means for applying a closure to the opening on the package, so formed.
13. A packaging machine, comprising a movable carrier; means for supplying a section of wrapping material to the carrier; means for deposition on the wrapping material, a portion of a product to be packaged; means for varying the size of the portion; means for forming the wrapping material about the product to form a sack like package; means for securing a wire or band about the free end of the package to serve as a closure thereto; means for trimming surplus wrapping material from the package; and means for coordinating the action of the several devices with the carrier for the purpose of performing the several operations on each package.

HAROLD C. SLOCOMB,
Administrator of the Estate of Elmer E. Slocumb, Deceased.

FRED W. McARDLE.
